UNITED STATES PATENT OFFICE.

CARL NELSON AND FRANK SNYDER, OF COUNCIL BLUFFS, IOWA.

CAR-DOOR.

1,380,831.

Specification of Letters Patent. Patented June 7, 1921.

Application filed July 7, 1920. Serial No. 394,424.

To all whom it may concern:

Be it known that we, CARL NELSON and FRANK SNYDER, citizens of the United States of America, and residents of Council Bluffs, in the county of Pottawattamie and State of Iowa, have invented certain new and useful Improvements in Car-Doors, of which the following is a specification:

This invention relates to doors for grain cars and particularly to novel means whereby a door may be held in the opening by means which are readily detachable to permit the door sections to swing outwardly to free the grain so that notwithstanding the pressure of the grain from within, the door may be manipulated to open it while at the same time the said door will withstand unusual pressure from within, without liability of opening or being displaced.

A still further object of this invention is to produce a door for a grain car having provision for supporting closure strips or at least the bottom of a series of closure strips above the door so that by use of the door and strips, the opening of a box car may be closed by means which are comparatively inexpensive and which will prove a saving of lumber or materials usually employed for this purpose.

A still further object of this invention is to provide a door comprising separable sections adapted to be anchored to the door frame with novel means for holding the separable sections together and guarding the joint between the two sections to prevent the escape of grain.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a view in elevation of a fragment of a box car with the closure embodying the invention applied thereto;

Fig. 2 illustrates a top plan view of the door in position with a fragment of the car in section;

Fig. 3 illustrates a view in elevation of the inner side of the door, and

Fig. 4 illustrates a sectional view through the door fastening.

In these drawings 5 denotes a box car, 6 the door frame, and 7 a series of boards or closure strips for closing the opening above the door.

The door in the present embodiment of the invention comprises a member 8 and a member 9 preferably constructed of lumber, each of said members being provided with vertically disposed plates such as 10 on its inner surface at the outer end. Each of said plates is secured to a member by fastenings 11 such as screws or nails, and each of the said plates and members has apertures 12 for the passage of securing devices 13 such as nails, it being the purpose of the inventors that the outer ends of the members shall be secured to the car frame by nails which will serve to retain them in place, it being the purpose also of the inventors that the nails shall be withdrawn as the door sections are forced outwardly in the center, thus making it possible to employ members which are nailed to the frame without liability of injuring the members owing to the fact that the plates 10 serve as protections to prevent splitting or other damage to the said members so that it is possible to use doors again and again when they are constructed in accordance with this invention.

The inner surfaces of the members near their inner ends are provided with plates 14 which are in the nature of wear plates to receive fastenings such as bolts 15 and 16, the former of which have their outer ends terminating in eyes 17 to receive the pins 18 for holding the members in assembled relation as will presently appear. The fastenings 16 retain the face plate 19 in place on the member 9 so that the member 9 carries the said face plate, and the said face plate extends across the joint 20 between the members 8 and 9 serving to seal the joint while at the same time it acts as a coupling for holding the parts in assembled relation owing to the fact that the said face plate has slots 21 which are occupied by the eyes 17 when the parts are in assembled relation, and the said face plate is therefore

locked in engagement with the member 8 as fully shown in Fig. 1.

An important element of this invention is found in the fact that the face plate 19 extends above the upper edges of the members 8 and 9 and forms a seat for the lowermost strip 7 which strip rests on the upper surfaces of the members 8 and 9 and against the rear surface of the face plate in such a manner that the members 8 and 9 are free to swing outwardly but are braced against inward movement by reason of engagement of the face plate with the outer surface of the lowermost strip 7; and the strip 7 is prevented from bulging in the center by reason of its contact with the face plate.

The plate 19 has a wear plate 22 on its outer surface which is engaged by the pins

18 so that notwithstanding there would be 20 relative movement of the face plate with relation to the bolt having the eye 17, the pins would not damage the said face plate.

We claim:

In a car door, door members separable 25 from one another, the said door members having metallic facings on their inner sides at the outer ends apertured to receive fastenings entering a door frame of a box car, a face plate adapted to lap the joint between 30 the said door members and project thereabove to form an abutment for a lowermost closure member above the door, and means for securing the face plate to the door members on opposite sides of the joint between 35 said door members.

CARL NELSON.
FRANK SNYDER.
